UNITED STATES PATENT OFFICE.

JACOB W. MEESE, OF HARRISBURG, PENNSYLVANIA.

DESIGN FOR A STATUE.

SPECIFICATION forming part of Design No. 21,533, dated May 10, 1892.

Application filed September 9, 1891. Serial No. 405,241. Term of patent 3½ years.

To all whom it may concern:

Be it known that I, JACOB W. MEESE, a citizen of the United States, residing at Harrisburg, in the county of Dauphin and State of Pennsylvania, have invented and produced a new and original Design for Statues, of which the following is a specification, reference being had to the accompanying drawing, forming a part thereof, which drawing is a front elevation of a statue representing my design.

The leading feature of my design consists of a figure of a man having the accepted facile features and expressions attributed to Christopher Columbus, which figure is mounted or superimposed upon a sphere representing the globe or earth. The globe or representation

of the earth, which is designated by the letter C, is mounted upon a base or pedestal A, the front side of which has a star. The sides of the base are provided with bas-reliefs. In 20 the drawing the figure D of Columbus is represented in an attitude of adoration or supplication, one knee resting upon the globe C, the hands being joined or clasped together and the eyes uplifted.

What I claim is—

The design for a statue or statuette, herein shown and described.

J. W. MEESE.
